UNITED STATES PATENT OFFICE.

CARL PIERCE LEWIS, OF BURLINGAME, CALIFORNIA, ASSIGNOR TO MINERALS SEPARATION NORTH AMERICAN CORPORATION, OF NEW YORK, N. Y., A CORPORATION OF MARYLAND.

FROTH-FLOTATION CONCENTRATION OF ORES.

No Drawing. Application filed August 4, 1926, Serial No. 127,180, and in Great Britain August 12, 1925.

This invention relates to the froth-flo-
tation concentration of ores, and is herein illus-
trated as applied to the differential flotation
of lead-zinc ores, for the collection of a lead
5 concentrate with the separate collection of
a zinc concentrate, if desired.

According to the present invention a froth
concentrate is separated by the aid of a flo-
tation agent which is mainly composed of a
10 soluble mineral-frothing agent, such as cre-
syllic acid or steam distilled pine oil, thereby
floating the desired value, nearly free from
any other normally floatable material. A
15 modifying agent, such as a cyanide, may be
used in addition to this flotation agent to in-
hibit the flotation of the other material, thus
for example facilitating the separation of
lead from zinc. The flotation agent used for
20 producing a second froth may also be mainly
composed of a soluble mineral-frothing agent,
such as cresyllic acid, or steam distilled pine
oil; and other agents may be used therewith.
In this way a large recovery of an exceed-
25 ingly rich lead concentrate may often be ef-
fected. Any iron present may be largely
kept out of both the concentrates.

Example 1.—Low grade ore from Keno
Hill, Alaska, was made into a pulp with water
and agitated with 0.15 pounds potassium cy-
30 anide, 0.10 pounds potassium xanthate, and
0.20 pounds cresyllic acid, all per ton of ore,
and a lead-bearing froth separated. The re-
sults are shown in the following table, from
35 which it will be seen that a large recovery of
the lead was effected in an exceedingly rich
concentrate, and that there was substantially
no concentration of the zinc with the lead.

	Assays			Recoveries	
	Wt. %	Pb. %	Zn. %	Pb. %	Zn. %
Heads.....	100.	4.86	3.5	100.	100.
Pb. conc.....	6.4	73.0	3.6	96.2	6.6
Pb. tail.....	93.6	.2	3.5	3.8	93.4

Example 2.—A pulp of an iron-bearing
lead-zinc ore from Mexico was agitated with
0.7 pounds of potassium xanthate, and 0.10
pounds cresyllic acid, both per ton of ore to
50 yield a lead concentrate, and then further
agitated with 4 pounds of lime, 1.2 pounds
copper sulphate, 0.2 pounds of potassium
xanthate, and 0.15 pounds of steam distilled
pine oil, all per ton of ore, and a zinc concen-

trate separated. The results are shown in 55
the following table.

	Assays			60
	Pb. %	Zn. %	Fe. %	
Heads.....	11.3	23.9	4.7	
Pb. conc.....	68.0	14.0		
Zn. conc.....	3.4	60.0		
Tails.....	.6	1.7		

Example 3.—A pulp of Nevada lead-zinc
ore, carrying some silver was similarly agi-
tated with the same agents in the same pro-
portion, to yield a lead concentrate and a
zinc concentrate, the results being shown in
70 the following table:

	Assays			75
	Ag. oz.	Pb. %	Zn. %	
Heads.....				
Pb. conc.....	25.9	10.8	11.9	
Zn. conc.....	6.7	1.2	50.2	
Tails.....	.10	0.4	1.2	

The indicated recovery of the lead in the 80
lead concentrate was 95.5%.

Example 4.—A pulp of ore from Federal
Morning Mine ore was agitated with po-
tassium cyanide 0.15 pounds, potassium xan-
thate 0.05 pounds, and cresyllic acid 0.1 pound,
85 all per ton of ore, and a lead-bearing froth
was separated. The pulp was then further
agitated with the further addition of copper
sulphate 0.6 pounds, lime 6 pounds, potassium
xanthate 0.2 pounds, and steam distilled pine 90
oil 0.15 pounds, all per ton of ore, and a
zinc-bearing froth separated partly as a fin-
ished concentrate and partly as a middling.
The results are shown in the following table:

	Assays			95
	Pb. %	Zn. %	Fe. %	
Heads.....	17.5	9.0	21.	
Pb. conc.....	64.4	9.6	6.	
Zn. conc.....	9.5	50.0	8.	
Zn. Midd.....	18.6	4.6	25.6	
Tails.....	2.4	.4	30.4	

Having thus described certain embodi-
ments of my invention what is claimed is:

1. The process of concentrating an ore con-
taining a floatable value and another nor-
mally floatable material which consists in

- agitating a pulp of the ore with a xanthate and with a flotation agent mainly composed of soluble mineral-frothing agent, to yield a froth rich in the floatable value, separating
- 5 the froth, further agitating with the addition of a further agent adapted to facilitate the floating of the other normally floatable material so as to yield a froth rich in said other normally floatable material, and separating
- 10 the froth.
2. A process of concentrating a lead-zinc ore which consists in agitating a pulp of the ore with a xanthate and with a flotation agent mainly composed of soluble-mineral froth-
- 15 ing agent, to yield a froth rich in lead, sepa-
- rating the froth, further agitating with the addition of a further agent adapted to facilitate the floating of the zinc so as to yield a froth rich in zinc, and separating the froth.
3. A process of concentrating a lead-zinc ore which consists in agitating a pulp of the ore with a xanthate and cresylic acid to yield a froth rich in lead, separating the froth, further agitating with the addition of pine oil to yield a froth rich in zinc, and sep- 25 arating the froth.
- In testimony whereof, I have affixed my signature to this specification.

CARL PIERCE LEWIS.
